(57) CLAIM

The ornamental design for a toy for children, as shown and described.

DESCRIPTION

FIG. 1 is a front elevational view of the toy for children, showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view thereof.

The broken line showing is for illustrative purposes only, and forms no part of the claimed design.
